UNITED STATES PATENT OFFICE.

CLEMENT L. V. MUNDHENK AND WILLIAM I. CHRISTIAN, OF WEST BALTIMORE, OHIO.

MAIL-POUCH FASTENER.

SPECIFICATION forming part of Letters Patent No. 615,876, dated December 13, 1898.

Application filed March 18, 1898. Serial No. 674,339. (No model.)

To all whom it may concern:

Be it known that we, CLEMENT L. V. MUNDHENK and WILLIAM I. CHRISTIAN, citizens of the United States, residing at West Baltimore, 5 in the county of Montgomery and State of Ohio, have invented certain new and useful Improvements in Mail-Pouch Fasteners; and we do hereby declare that the following is a full, clear, and exact description of the invention, which will enable others skilled in the art to which it appertains to make and use the same, reference being had to the accompanying drawings, and to the letters of reference marked thereon, which form a part of this 10 specification.

Our invention relates to improvements in mail-pouch fasteners, and has for its object the provision of simple and reliable means for fastening the flap to the body of the mail-pouch, as will be hereinafter fully described in connection with the accompanying drawings, of which—

Figure 1 is a view of the upper portion of a mail-pouch, to which our fastening devices 25 are attached. Fig. 2 is a cross-section through one of the fasteners and the mail-pouch. Fig. 3 is a detached edge view of one of the flap-plates and bolt. Fig. 4 is a detached view of the main lock. Fig. 5 is a detached view of 30 one of the covers.

A and B designate the two sides of the pouch or sack, and C is the flap, a continuation of said side B.

a designates a series of plates riveted to the 35 inner side of the flap, and each of which has a bolt b projecting from it. c designates a similar number of plates secured to the inside of part B, near the mouth of the sack. All of these plates are connected at their upper ends by hinges c'.

d designates a series of sliding bars having flexible connections d' and movable in guides

d'', projecting from the plates c. e designates a dog pivoted at e' to each of said plates and normally controlled by springs e'' to throw 45 them into engagement with the bolts b. The sliding bars d have each a pin f, which comes in contact with the said dogs when the said bars are drawn in the direction of the arrow. This enables the bolts to enter the openings 50 g in covers c'' and to assume positions for the dogs to engage therewith when the said bars d are released.

h designates a series of plate-springs attached to the inner sides of the plates c and 55 lying across the openings g. When the bars d are drawn to remove the dogs from engagement with the bolts b, these springs force the bolts out of said openings, and the flap is then in a position to be thrown open. The bars d 60 are secured by means of a lock, the bolt K of which engages with a notch i in one of said bars.

Having described our invention, we claim—

The combination with a mail-pouch, of a series of plates hinged together, and having each a spring-controlled pivotal dog, a series of sliding bars flexibly connected and having pins adapted to engage with said dogs, a series of plates attached to the flap of said pouch 70 and each having a bolt to engage with a respective dog, and a series of springs to press said bolts outward when the latter are released by the dogs, as herein shown and described.

In testimony that we claim the foregoing as our own we hereto affix our signatures in presence of two witnesses.

CLEMENT L. V. MUNDHENK.
WILLIAM I. CHRISTIAN.
